UNITED STATES PATENT OFFICE

2,541,222

TICKET HOLDER AND RECEIPT DISPENSER

Alphonsus Chester Egart, Detroit, Mich., and
George Michael Egart, Chicago, Ill.

Application June 8, 1948, Serial No. 31,823

7 Claims. (Cl. 206—40.6)

1

This invention relates to ticket holders and receipt dispensers, and has for its principal object to provide a simple, economical and sturdy device by means of which the operator of a bus can quickly and correctly tear a ticket to form an identification receipt for the passenger, indicating the station at which he boarded and the station to which he is destined, and an auditor's record of the same transportation giving like information.

The tickets used each comprises an oblong sheet of paper ruled lengthwise and crosswise and provided with horizontal and vertical lists of stations in duplicate. By tearing a ticket crosswise at a line corresponding to the boarding station and providing a notch or pointer on a line indicating the destination station, the parts of the ticket form a permanent record of the transaction in duplicate.

In use, a pad of such tickets will be put in the ticket holder and receipt dispenser, placed convenient to the hand of the operator, who by simple manipulation can issue an identification receipt to each passenger and retain a corresponding auditor's record on the pad to be turned in at the end of the run.

Fig. 1 is a side elevation of the device attached to a stanchion or post in the vehicle;

Fig. 2 is a front elevation of the device;

Fig. 3 is a perspective view of the pad of tickets 30 and a holder called a bed or carriage;

Fig. 4 is a vertical section through the assembly;

Fig. 5 is a transverse section on the line 5—5 of Fig. 2;

Fig. 6 is a vertical section along the center line of the device;

Fig. 7 is a cross section on the line 7—7 of Fig. 6; and

Fig. 8 is a diagrammatic representation of the passenger's identification receipt.

But these specific drawings and the corresponding description are used for the purpose of disclosure only, and are not intended to impose unnecessary limitations on the claims.

The base of the device is an elongated channel of sheet metal or the like comprising a web 10, side flanges 11 and 12, and wing flanges 13 and 14.

Upper and lower attaching brackets 15 and 16 comprising somewhat U-shaped straps are welded to the end portions of the flanges 11, 12, 13, and 14, and are provided with bolts 17 and clips 18 by which the base, and therefore the device, may be readily mounted on a post or stanchion 19 in the vehicle.

The pad of tickets 20 is mounted upon and 55 or forwardly (Fig. 5) and inwardly at 44 to

2

carried by a bed or carriage movable lengthwise or up and down in the base along the web 10 between the flanges 11 and 12. The bed or carriage includes a bottom channel composed of a web 21 and flanges 22 and a top channel composed of a web 23 and flanges 24; the two channels being yieldingly urged apart by a long leaf spring 25 having its end portions 26 bearing against the web 21 and its intermediate portion 27 bearing against the web 23 to constantly urge the two channels apart, and thereby automatically adjust the thickness of the bed.

The two channels and the spring are held in assembled relation by laterally directed lugs 28 on the flanges 24 projecting into slots 29 in the flanges 22.

The pad 20 is located on the bed by a non-circular stud 30 passing through a slot 31 in the lower end of the pad 20. The stud is fixed to the web 21 of the lower channel of the bed and projects through slots 32 in the spring 25 and 33 in the web 23 of the upper channel with appropriate clearance. The clearances are such that the upper channel may be tilted slightly in order to enter the lugs 28 in the slots 29 while the spring 25 is compressed; after which the reaction of the spring serves to hold the channels in substantially parallel relation, and hence the lugs 28 in the slots 29.

The bed or carriage is movable lengthwise along the base in order to place the appropriate horizontal line under a tearing strip or ruler when a passenger has paid his fare and the operator desires to tear off the appropriate identification slip. This is accomplished by attaching the carriage to an operating lever 35 fulcrumed on a pin 36 fixed to the left wing 14 of the bed and adapted to rotate about that fulcrum up and down from the position shown in Fig. 2. In order to pass behind the base, the lever has an arched portion 37 which lies across the web 10 of the base, as best shown in Figs. 2, 5, and 6. The arched portion is connected to the web 21 of the lower channel of the bed or carriage by means of a stud 39 fixed to that web and projecting through a vertical slot 40 in the web 10 of the base and a horizontal slot 41 in the arched portion 37 of the lever 35. It is made fast by a cap 42 and a cap screw 43. From this connection, it will be apparent that moving the lever about its fulcrum 36 will cause the stud 39 to travel in the slot 40, and thereby move the bed or carriage lengthwise up or down along the base according to the direction of movement of the lever 35.

The free end of the lever 35 is turned upwardly

close about a circular or sector-shaped flange 45 on the right wing flange 13 of the base. That portion of the lever 35 is equipped with a hollow handle 46 in which there is a spring 47 normally urging a friction shoe or plunger 48 against the flange 45 to retain the lever, and therefore the carriage, in a set position.

In order to enclose and properly hold the pad of tickets 20, the bed or carriage is provided with a concave cover or housing 50 having one side 51 hinged at 52 to the flange 11 of the base and the other side 53 equipped with a latch 54 adapted to extend through a slot 55 in the wing flange 14 and engage the latter at 56 to hold the cover in normally closed position.

Inside the cover there is a long leaf spring 57 adapted to lie on the pad of tickets shown in Fig. 4 and urge them constantly against the bed or carriage. Preferably, the spring is slotted along the middle 58 to make it forked, and the ends of the forks are rounded, as indicated at 59. The lower end of the spring 57 is turned at an angle and made fast to the bottom 60 of the cover, as indicated at 61 (Fig. 6).

The top 62 of the cover provides a straight edge 63 which lies across the top of the uppermost ticket and forms a tearing edge or ruler against which the free end of the ticket may be pulled to tear off the identification check or receipt.

Just beneath the top 62 of the cover and adjacent to the cutting edge 63, there is a curved metal clip 64 pivoted on a rod 65 and urged by a spring 66 to bring its edge 67 to the right in Fig. 6 or toward the carriage, whereby it will always tend to hold the stubs 68, as shown in Fig. 4, inside the cover so as to expose the ticket to be operated upon to the cutting edge 63.

With such an arrangement, no matter how many of the auditor's stubs 68, or how many different lengths are on the pad, by moving the carriage downwardly to bring the longest stub below the clip 64 and moving it upwardly again, the clip 64 will gather the stubs and curl them to substantially the position shown in Fig. 4 within the cover 50, and thereby expose the topmost ticket to be operated upon.

In order to cut a notch or other indication in the auditor's stub and identification receipt at a point indicating the destination of the passenger, the cover is provided with a pointer 70 mounted to slide back and forth in a recess 71 in the top of the cover and along a transverse rod 72 in order to bring a short point 73 at the proper location with respect to the vertical lines on the ticket 20 to indicate the station of destination. The pointer is formed up of sheet metal of the shape generally indicated in Figs. 2, 6, and 7 and is pierced transversely to fit on the rod 72 between the shoulders 74 at each side of the depression 71 in the cover 50.

The rod 72 is made readily removable by providing it with a notch 75 adapted to receive a forked end of the latch 76 slidable within the cover 50 under a holding rivet 77. By releasing the latch, the rod can be removed far enough to permit the pointer 70 to be taken out for sharpening, and to permit replacing it.

In operation, the latch 54 (Fig. 5) is pressed to the right, releasing the cover 50, which is swung about the hinge 52 to open position. A pad 29 is inserted, and the stud 30 put through the slot 31. The upper ends of the tickets lying between the shoulders 80 on the upper end of the flanges 22 and underneath the finger 81 are best shown in Fig. 3. The cover is closed. When a passenger

pays his fare, the operator, grasping the handle 46, shifts the lever 35, and therefore the carriage and the pad of tickets, until the horizontal line, or some portion corresponding to the horizontal line for a station, comes beneath the cutting edge 63 at the top of the cover. Next, he moves the pointer 70 to move the point 73 beneath the station of destination, and finally, by picking up the upper end of the top ticket and pulling it across the cutting edge 63, he tears off the identification receipt or check, simultaneously marking the station of boarding and cutting a notch to indicate the station of destination. The receipt handed to the passenger serves as identification, and when turned back to the operator at the station of departure indicates whether or not the passenger has paid for transportation to that station.

After removal of identification receipt or check, the operator will lower the lever 35 to bring the upper end of the auditor's coupon within the grasp of the clip 64, and then raise the lever again to bring the next ticket with the appropriate station line in the vicinity of the cutting edge 63, and repeat the operation described.

We claim:

1. In a ticket holder and receipt dispenser, a base, a cover on the base providing a cutting edge extending across a ticket bed hereinafter described, a retaining spring attached at one end to said base and operating against the ticket bed under said cover, a ticket bed movable lengthwise along said base and having therein a ticket pad support, an elongated leaf spring resting on a bottom web of the ticket bed and engaging said support to direct the support against the cutting edge of said cover and against the retaining spring, an operating lever across the back of said base fulcrumed on one side thereof and connected to said bed by a stud operating in a slot to move the bed along the base in direct response to a corresponding movement of the lever, a continuous friction segment carried by the base opposite the fulcrum and providing an unbroken friction surface curved in an arc corresponding substantially to the path of the lever when rotated, friction means carried by the lever adjacent said segment to engage the segment for holding the bed in any adjusted position, a spring-actuated arcuate clip under the cover adjacent said cutting edge for engaging and directing ticket stubs within said cover, and a removable pointer slidably adjustable along the cutting edge of the cover transversely across said bed.

2. In a ticket holder and receipt dispenser, a base, a cover on the base providing a cutting edge extending across a ticket bed hereinafter described, a ticket bed movable lengthwise along said base and having therein a ticket pad support, an elongated leaf spring resting on a bottom web of the ticket bed and engaging said support to direct the support against the cutting edge of said cover, an operating lever across the back of said base fulcrumed on one side thereof and connected by a stud operating in a slot intermediate the ends of the lever to said bed to move the bed along the base in direct response to a corresponding movement of the lever, a continuous friction segment carried by the base opposite the fulcrum providing an unbroken friction surface curved in an arc corresponding substantially to the path of the lever when rotated, friction shoe carried by the lever adjacent said segment to engage the segment for holding the bed in any adjusted position, a spring-actuated

arcuate clip under the cover adjacent said cutting edge for engaging and directing ticket stubs within said cover, and a removable pointer slidably adjustable along the cutting edge of the cover transversely across said bed.

3. In a ticket holder and receipt dispenser, a base, a cover on the base providing a cutting edge extending across a ticket bed hereinafter described, a ticket bed movable lengthwise along said base and having therein a ticket pad support, an elongated leaf spring resting on a bottom web of the ticket bed and engaging said support to direct the support against the cutting edge of said cover, an operating lever at the back of said base fulcrumed on one side thereof and connected to said bed by means of a stud and slots associated with the bed and lever to move the bed along the base in direct response to a corresponding movement of the lever, a continuous friction segment carried by the base opposite the fulcrum providing an unbroken friction surface curved in an arc corresponding substantially to the path of the lever when rotated, and friction means carried by a handle of the lever adjacent said segment to engage the segment for holding the bed in any adjusted position.

4. In a ticket holder and receipt dispenser, a base, a cover on the base providing a cutting edge extending across a ticket bed hereinafter described, a ticket bed movable lengthwise along said base and having therein a ticket pad support, an elongated leaf spring resting on a bottom web of the ticket bed and engaging said support to direct the support against the cutting edge of said cover, an operating lever across the back of said base fulcrumed on one side thereof and connected to said bed by a stud and slot arrangement in the bed and lever to move the bed along the base in direct response to a corresponding movement of the lever, means associated in frictional engagement with a handle of the lever located opposite the fulcrum and with an adjacent segment of the base for holding said bed in any adjusted position, and a spring-actuated arcuate clip under the cover adjacent said cutting edge for engaging and directing ticket stubs within said cover.

5. In a ticket holder and receipt dispenser, a base, a cover on the base providing a cutting edge extending across a ticket bed hereinafter described, a ticket bed movable lengthwise along said base and having therein a ticket pad support, an elongated leaf spring resting on a bottom web of the ticket bed and engaging said support to direct the support against the cutting edge of said cover, an operating lever across the back of said base fulcrumed on one side thereof and connected to said bed by a stud and slot arrangement in the bed and lever to move the bed along the base in direct response to a corresponding movement of the lever, frictional means associated with the lever and with an arcuate segment of the base opposite the fulcrum for hold-

ing the bed in any adjusted position, and a spring-actuated arcuate clip under the cover adjacent said cutting edge for engaging and directing ticket stubs within said cover.

5 6. In a ticket holder and receipt dispenser, a base, a cover on the base providing a cutting edge extending across a ticket bed hereinafter described, a retaining spring attached at one end to said base and operating against the ticket bed under said cover, a ticket bed movable lengthwise along said base and having therein a ticket pad support, an elongated leaf spring resting on a bottom web of the ticket pad and engaging said support to direct the support against the cutting edge of said cover and against the retaining spring, an operating lever across the back of said base fulcrumed on one side thereof and connected intermediate the ends of the lever to said bed by means of a stud and slot arrangement in the bed and lever to move the bed along the base in direct response to a corresponding movement of the lever, frictional means associated with the lever and with the base opposite the fulcrum for holding the bed in any adjusted position, and a spring actuated arcuate clip under the cover adjacent said cutting edge for engaging and directing ticket stubs within said cover.

30 7. In a ticket holder and receipt dispenser, a base, a cover on the base providing a cutting edge extending across a ticket bed hereinafter described, a retaining spring attached at one end to said base and enclosed by said cover, a ticket bed movable lengthwise along said base and having therein a ticket pad support, an elongated leaf spring resting on a bottom web of the ticket bed and engaging said support to direct the support against the cutting edge of said cover and against the retaining spring, an operating lever across the back of said base fulcrumed on one side thereof and connected to said bed intermediate the ends of the lever by means of a stud and slot arrangement to move the bed along the base in direct response to a corresponding movement of the lever, a continuous friction segment carried by the base opposite the fulcrum providing an unbroken friction surface curved in an arc corresponding substantially to the path of the lever when rotated, and a friction shoe carried by the lever to engage said segment for holding the bed in any adjusted position.
